UNITED STATES PATENT OFFICE

151,414

DESIGN FOR A VEGETABLE SLICER

Frederick R. Smith, Toledo, Ohio

Application October 24, 1946, Serial No. 134,190

Term of patent 14 years

(Cl. D89—1)

To all whom it may concern:

Be it known that I, Frederick R. Smith, a citizen of the United States, residing at Toledo, county of Lucas, and State of Ohio, have invented a new, original, and ornamental Design for Vegetable Slicer, of which the following is a specification, reference being had to the accompanying drawings, forming part thereof.

In the drawing,

Figure 1 is a side elevational view of the vegetable slicer, showing my new design;

Figure 2 is a top plan view of the vegetable slicer illustrated in Figure 1;

Figure 3 is a front elevational view of the vegetable slicer, and

Figure 4 is a rear elevational view of the vegetable slicer.

I claim:

The ornamental design for a vegetable slicer, substantially as shown.

FREDERICK R. SMITH.
